UNITED STATES PATENT OFFICE.

MOSES T. RIDOUT AND EDGAR M. RIDOUT, OF HUTCHINSON, MINNESOTA,
ASSIGNORS OF ONE-HALF TO CHESTER G. RIDOUT AND WARREN D.
GRAHAM, OF SAME PLACE.

CLEVIS.

SPECIFICATION forming part of Letters Patent No. 496,957, dated May 9, 1893.
Application filed February 25, 1893. Serial No. 463,722. (No model.)

To all whom it may concern:
Be it known that we, MOSES T. RIDOUT and
EDGAR M. RIDOUT, citizens of the United
States, residing at Hutchinson, in the county
of McLeod and State of Minnesota, have in-
vented certain new and useful Improvements
in Clevises, of which the following is a speci-
fication.

Our invention relates to clevises, and con-
sists in a novel construction of the same as
hereinafter set forth and claimed.

In the drawings,—Figure 1 is a perspective
view of our improved clevis; Fig. 2, a side
elevation partly in section, but with the parts
in a different position; and Fig. 3, a face view
of the pivoted block.

A indicates the frame of our clevis, which
may be attached to the frame of the plow beam, as may be preferred. This
frame comprises two forwardly-extending
arms, a, between which is pivoted upon the
bolt B, the block C. This block C is provided
on its lower rear face with a seat b; and, near
its upper end with two series of holes, c and
d; the latter being designed to be brought
into line with corresponding holes e in the
arms a of frame A, so that the wooden break-
pin D may pass through the holes in the block
and the frame, or pass through the block and
rest upon the frame. When the pin D is passed through
one of the holes c, it will rest upon the top of
the arms of frame A, as will readily be un-
derstood upon reference to Fig. 1. When,
however, the pin is inserted in the holes d
and e, a slightly increased force is required to
break the pin by reason of the fact that the
pin is supported firmly at each end by the
frame instead of merely resting upon the lat-
ter. In order, however, to effect a material
difference, the pin may be placed nearer to or
farther from the axis or bolt, as required.

Block C, when in its normal position, has
its lower end in proximity to a forwardly ex-
tending lug E secured to the frame A,—said
lug serving to support the plow when
the plow is not in use. The whiffletree F when
provided with a staple or eye f which encircles
the lower end of the block C when encircles
upon the arm or lug E.

G indicates a loop B or bail, pivoted at its
ends upon the bolt B and lying normally up

on top of block C as shown in Fig. 1. Secured
to one end to the bail G, and at the other end
to the eye or staple f, is a chain g which is
normally out of action.

The operation of the device is as follows:
Now with the parts in the position shown in
Fig. 1, and the team pulling upon the whif-
fletree, there will be no change in the position
of the parts until the plow meets with an ob-
struction which presents a greater resistance
than is presented by the wooden pin. When
this occurs, the pin will break, and the block C
will be rocked upon its pivot, and the eye or
staple will ride off the lower end of the block.
As the horses continue to pull, the chain, at-
tached to the eye, will be pulled, the block C
stretched taut, and the link or bail brought
to a horizontal position as shown in Fig. 2,—
thus keeping the whiffletree off the horses'
heels and maintaining a connection with the
plow. By merely tightening the nut on the
bolt B, or by using a leather washer, the bail
may be held in the position shown in Fig. 1,
notwithstanding the jars or light shocks to
which the plow is subjected,—and at the
same time leaving it free to be swung down
when necessary.

Having thus described our invention, we
claim is—

1. In combination with the clevis frame
D; the block C pivoted therein; the break-
pin D; the whiffletree provided with a staple
or bail pivoted to the lower end of the block; and the
block pivoted to the frame A; and a cle-
vis connected at one end with the loop

2. In combination with the clevis
and the block C pivoted therein; the cle-
vis pin D; and the block lug or projection E in
the frame to support the whiffletree

3. In combination with the clevis
having the holes e; the pivoted block
with two series of holes c and d; a
pin adapted to fit said holes.

In witness whereof we here-
unto affix our hands in the presence of two wit-
nesses:

EDGAR M.

JOHN KNAPP,
A. P. WOODWARD.
